UNITED STATES PATENT OFFICE.

LLOYD G. COPEMAN, OF FLINT, MICHIGAN.

COLLAPSIBLE MOLDING DIES.

Application filed January 17, 1924, Serial No. 686,884.

To all whom it may concern:

Be it known that I, LLOYD G. COPEMAN, a citizen of the United States, residing at Flint, in the county of Genesee and State of Michigan, have invented certain new and useful Improvements in Collapsible Molding Dies, of which the following is a specification.

This invention relates to collapsible molding dies used primarily for casting stone refrigerator shells. It is sometimes desirable to cast refrigerator shells having walls of uniform thickness. To cast such walls requires dies that will recede from the casting as the dies are withdrawn. It has been customary to accomplish this by providing sufficient draft to the cast shell, i. e., having the bottom of the casting of greater thickness than the top, so that as the inner die is removed the die will pull away from the surface of the casting.

The object of the present invention is to form a shell casting having walls of uniform thickness, the inner dies or cores being withdrawn from the casting in sections, the same receding from the casting as they are withdrawn. Another object is to provide collapsible dies which can be readily and easily located and locked into place, but which are readily removed after the casting has set.

In the drawings I have shown simply a collapsible mold for forming a rectangular shell, but obviously this principle of tying the collapsible molds together could be utilized in a more complicated casting; it simply means the addition of more rectangular molds all joined together to accomplish the desired result.

In Figs. 11 and 12 I have shown a modified construction showing a more complicated casting. It will be obvious that any complicated casting can be made without departing from the principle of the invention.

In the drawings:

Fig. 1 is a plan view of the inner core or dies assembled together.

Fig. 2 is a detail in perspective of a portion of a corner post used for tying the collapsible mold parts together.

Fig. 3 is a detail in perspective of one corner of one of the side members of the collapsible die.

Fig. 4 is a detail in perspective showing

how the side member is fitted onto the bottom plate.

Fig. 5 is a section on the line 5—5 of Fig. 4, showing the locking means.

Fig. 6 is a detail in perspective of a portion of the anchoring bracket.

Fig. 7 is a section on the line 7—7 of Fig. 1.

Fig. 8 is a transverse section through the mold parts showing the inner die inverted and the outer dies secured to the base plate for pouring the cement.

Fig. 9 is a section on the line 9—9 of Fig. 8.

Fig. 10 is a sectional detail showing how the side members are withdrawn from the casting.

Fig. 11 is a plan view of a modified form of casting.

Fig. 12 is a section on the line 12—12 of Fig. 11.

The inner core or die is formed of a bottom wall *a*, side walls *b* and *c*. The bottom is constructed with a groove *d* formed by cutting away a portion of the wall and securing to said cut-away portion a strip *e*. The strip *e* is of less width than the cut-away portion which leaves the groove *d* adjacent the inner edge of the wall but set in slightly from the edge of the plate. The wall *a* is preferably made of wood or other fibrous material and the strip member *e* is of metal, as it is this portion of the bottom which takes the most wear. Secured to the side walls are L-shaped brackets *f* provided with the downturned tongues *g* which are adapted to engage in the groove *d* as the side walls are fitted onto the bottom. A stud *h* is carried by the wall *e* and extends through a slot *i* cut into the L-shaped bracket *f*. A plurality of these studs and slots are used. The side walls are correctly located with respect to the bottom by the grooves and studs. A thumb nut *j* is screwed onto each stud *h* and securely holds the side walls in the correct position.

After the side walls have been secured to the bottom the corner posts *k* are then slipped into place. Here we have a novel way of locking the side walls together by means of a tongue-and-groove arrangement between the posts and the side walls. More in detail, referring to Figs. 2, 3 and 4, it will be seen that the side walls are formed principally of wood or other fibrous mate-

rial, the edges that abut against the post being bound with a special form of angle iron casting which is provided with a tongue *m*. This tongue is inclined to the vertical as shown in Figs. 3 and 4, and the posts *k* are also bound with a metal shell which is provided with the grooves *n* in the side thereof adapted to register with the inclined tongues *m*. These posts are fitted onto the corners between the side walls and as the same is forced in the sliding tongue-and-groove arrangement brings the post to its proper position and securely locks the end walls together. The side walls are formed with a hook or stop *o* (see Fig. 3) and the posts are provided with corresponding notched portions *p* which are engaged by said hooks so as to lock the posts and side walls together.

Refer now to Figs. 7 to 10 inclusive. The inner core or box formed of these walls and posts is now inverted and set onto a plate *q*. This plate is provided with a rectangular rib *r* for locating the inner box core thereon (see Fig. 8). The outer dies *s* are formed of a plurality of walls secured together, which are set onto the plate *q*, and are bolted thereto by means of the studs and thumb nuts *t*. The mold is now ready to be filled with the casting material. The material I use for casting refrigerator shells is preferably oxy-chloride cement which is poured while cold, the characteristic of which permit the same to readily flow about the mold and to form a solid stone casting when the material is set.

To withdraw the dies from the casting, the complete mold is turned over, the plate *q* is removed so that access may be had to the interior of the inner box core; the thumb nuts *j* are removed and one of the side walls is lifted vertically. A reference to Fig. 10 will make plain the purpose of the inclined tongue-and-groove between the side walls and the corner posts. As the wall is lifted upwardly the tongue-and-groove arrangement causes the wall to recede from the inner face of the casting and permits the ready removal of the walls, leaving the corner posts in place.

The corner posts may now be knocked in and removed and the bottom lifted out. The outer die plates are then unbolted and are merely drawn away from the casting.

By utilizing this slanting tongue-and-groove arrangement between the walls and corner posts, it is possible to withdraw the inner core without disturbing the casting. Such a collapsible die permits the casting of a shell having a uniform thickness, and also a casting having a tapered wall; that is, a wall having a thickness greater at one end than at the other. By referring to Fig. 10 it will be seen that the upper part of the shell, designated *X* could be of greater

thickness than the lower part as shown by the dotted line, it being necessary however, that the inclination of the tongue and grooves should have a greater angle with respect to the vertical than the taper of the wall so that as the side wall is lifted it will recede from the casting. If the taper to the shell runs in the opposite direction, the side walls can be lifted straight up, through the use of the tongue-and-groove permits a better removal of the core and prevents the breaking or scraping of the casting by the removal of the core members.

What I claim is:

1. In a molding apparatus, a collapsible molding core provided with side walls and a bottom wall, and means requiring the side walls to draw in away from the casting as the side walls are removed from the bottom wall.

2. In a molding apparatus, a collapsible molding core provided with side walls and a bottom wall which fit and lock together and in which the side walls may be disengaged from the bottom wall and from each other by a movement directly away from the bottom wall, but which at the same time tends toward the center of the core.

3. In a molding apparatus, a collapsible core provided with a plurality of side walls and a bottom wall and corner posts, all of the said elements locking together and the corner posts arranged to require the side walls to move inwardly toward the center of the core when the same are drawn away from each other and from the bottom wall.

4. In a molding apparatus, a collapsible core comprising a plurality of side walls and bottom wall and grooved corner posts for locking the said elements together, the said grooves in the corner posts being so arranged as to cause the side walls to tend away from the casting when the side walls are withdrawn.

5. In a molding apparatus, a collapsible core provided with a plurality of side walls, bottom wall and interlocking corner posts which are provided with inclined grooves, the said side walls interlocking with the posts and in the said inclined groove whereby when the side walls are withdrawn from the core they assume a movement toward the center of the core to separate from the casting.

6. In a molding apparatus, a collapsible core comprising a plurality of side walls, a bottom wall provided with a plurality of grooves, the said side walls being arranged to fit within the said grooves to locate them with respect to the bottom wall, and means for locking the side walls to each other and also to the bottom wall in detachable relation so the core can be collapsed.

7. In a molding apparatus, a collapsible core comprising a bottom wall provided with

a plurality of grooves, a plurality of side walls having angle members on the bottom provided with lips adapted to fit into the said grooves of the bottom wall to locate the 5 side walls on the bottom wall, and means for locking the angle members to the bottom wall in detachable relation.

8. In a molding apparatus, a collapsible core comprising a bottom wall with a plurality of grooves, a plurality of side walls

having tongues on their ends and angle members on their bottoms provided with lips adapted to fit into the grooves to position the side walls on the bottom wall, and corner posts provided with inclined grooves ¹⁵ into which the side walls' tongues fit at their ends.

In testimony whereof I have affixed my signature.

LLOYD G. COPEMAN.
